UNITED STATES PATENT OFFICE.

HOMER McDANIEL, OF CANTON, OHIO.

DESIGN FOR A GAME-BOARD.

SPECIFICATION forming part of Design No. 22,976, dated December 19, 1893.

Application filed October 25, 1893. Serial No. 489,135. Term of patent 3½ years.

To all whom it may concern:

Be it known that I, HOMER McDANIEL, a citizen of the United States, and a resident of Canton, county of Stark, State of Ohio, have 5 invented and produced a new Design for a Game-Board, of which the following is a full, clear, and exact description, reference being had to the accompanying drawing, making part of this specification.

10 My design relates to game boards.

In the drawing I have shown in perspective, the game board which has straight parallel edges *a*, terminating in a rounded forward end *b*, and a straight rear end *c*, at right angles to the side edges; a flange strip *d* projects upwardly entirely around the curved end. Near the forward end of the board, a series of horizontal lines *e* is intersected by 15 a series of vertical lines *f*, which form a square

divided into blocks *g*. At the upper end of the square is a semi-circle *h*.

The leading features of my design are the board having parallel edges, a rounded forward end, a curved strip or flange, horizontal and vertical intersecting lines forming blocks, 25 a semi-circular line at the forward end of the blocks.

Having thus described my design, I claim—

The design for a game board herein shown and described. 30

In testimony whereof I have hereunto set my hand this 30th day of September, A. D. 1893.

HOMER McDANIEL.
